BLOW-GUN TOY

Fred Waynai, Syracuse, N. Y.

Application January 6, 1955, Serial No. 33,856

Term of patent 14 years

(Cl. D34—15)

FIG. 1

FIG. 2

FIG. 3

FIG. 4

The missile, attached to the gun by a string, is shown in position for launching in Figure 1 and in flight in Figures 2 and 3.

I claim:

The ornamental design for a blow-gun toy, substantially as shown and described.
